ATTYS

UNITED STATES PATENT OFFICE.

MAX R. BRUECHE, OF BLOOMFIELD, NEW JERSEY, ASSIGNOR TO SILAS SWARTZ, OF NEW YORK, N. Y.

LAPEL-BUTTON.

SPECIFICATION forming part of Letters Patent No. 645,501, dated March 13, 1900.

Application filed July 13, 1899. Serial No. 723,643. (No model.)

To all whom it may concern:

Be it known that I, MAX R. BRUECHE, a citizen of the United States, and a resident of Bloomfield, Essex county, New Jersey, have 5 invented certain new and useful Improvements in Lapel-Buttons, of which the following is a specification.

My invention relates to lapel buttons or pins of the kind usually used for campaign-badges 10 or for advertising or ornamental purposes.

The object of my invention is to furnish such a button or pin that will permit of the same being readily attached to and detached from the garment and when so attached to be 15 retained thereon and which can be made much more reasonably than those now in use.

My invention consists, essentially, of such a button or pin provided upon its back with teeth on opposite sides of and setting out from 20 the same and pointing toward each other. My invention also consists of said teeth forming part of a flanged ring which sets out from the back. My invention also consists in certain other features and details, as more particularly 25 hereinafter described.

In the accompanying drawings, Figure 1 illustrates a back view of a button or pin made in accordance with my invention. Fig. 2 is a cross-section of the same. Fig. 3 is a back 30 view of another form of button to that shown in the preceding figures, and Fig. 4 is a cross-section of the same.

Similar letters represent like parts in all the figures.

35 A is the body of the button, which is in the form of a disk, and B is a flanged ring, the flanged edge *b* of which incloses and is secured to said body A. The ring B is provided with two teeth or spurs *c c* on opposite sides extending toward each other and which set out 40 a little from the back of the body A.

D is a flanged ring, which surrounds the edge of the ring B and retains both the ring B and the body A, the flat portion *d* of the said ring

45 D overlapping the front of the body A. The teeth *c c* are cut out of the back portion of the ring B (which is the extreme back part of the button) and are virtually on the same plane as said back portion. These teeth catch 50 and bite the cloth of the garment between them, there being room for the cloth between

the teeth and the back of the body A. The button can be as readily attached to the garment and be as readily removed therefrom as a button having an ordinary pin, and my improved 55 button will hold upon the garment as securely as is needed. The teeth *c c* being cut out of the same piece of metal as the ring B renders the button much less expensive than if provided with a pin for attachment to the gar- 60 ment.

In the construction shown in Figs. 3 and 4 the body E and ring F are struck up from the same piece of metal, so as to leave an annular recess *f* between said body and ring, and 65 the flanged edge *b* of the ring B is inclosed and held in said annular recess *f* of the ring F.

What I claim as new, and desire to secure by Letters Patent, is—

1. A lapel or ornamental button consisting 70 of a body, a flanged ring secured thereto, and said ring provided with teeth on opposite sides setting out from the back of the body and pointing toward each other, as and for the purposes set forth.

2. A lapel or ornamental button, consisting of a body, a flanged ring inclosing said body and secured thereto, and said ring provided with teeth on opposite sides setting out from the back of the body and pointing toward each 80 other, as and for the purposes set forth.

3. A lapel or ornamental button consisting of a disk-shaped body a flanged ring secured thereto, and said ring provided with teeth on opposite sides setting out from the back of 85 the body and pointing toward each other, as and for the purposes set forth.

4. A lapel or ornamental button, consisting of a body, a flanged ring inclosing said body and secured thereto, and said ring provided 90 with teeth on opposite sides setting out from the back of the body and pointing toward each other and another ring surrounding and retaining therein the toothed ring, as and for the purposes set forth.

In testimony whereof I have signed my name to this specification in the presence of two subscribing witnesses.

MAX R. BRUECHE.
